DESIGN FOR A BOTTLE

Frederick E. Parsons, Philadelphia, Pa., assignor
of fifty one-hundredths to Frederic Jewell Bux-
ton, Philadelphia, Pa.

Application May 9, 1940, Serial No. 92,247

Term of patent 3½ years

To all whom it may concern:

Be it known that I, Frederick E. Parsons, a citizen of the United States, residing in Philadelphia, county of Philadelphia, State of Pennsylvania, have invented a new, original, and ornamental Design for a Bottle, of which the following is a specification; reference being had to the accompanying drawing, forming a part thereof, showing my new design for a bottle, and in which:

Figure 1 is a top plan view of a bottle showing my new design.

Figure 2 is a front elevation; and

Figure 3 is a rear elevation.

I claim:

The ornamental design for a bottle, substantially as shown.

FREDERICK E. PARSONS.
